(57) **CLAIM**

The ornamental design for a golf green drink coaster, as shown and described.

DESCRIPTION

FIG. 1 is a top perspective view of a golf green drink coaster showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a top perspective view of an alternate embodiment of FIG. 1;

FIG. 9 is a rear elevation view of FIG. 8;

FIG. 10 is a front elevation view of FIG. 8;

FIG. 11 is a top plan view of FIG. 8; and,

FIG. 12 is a bottom plan view of FIG. 8.

The broken line illustrations of the drinking glass shown in the views are for illustrative purposes only, and form no part of the claimed design.
